JAMES N. MACRAE, OF STAMFORD, CONNECTICUT, ASSIGNOR TO PETROLEUM HEAT AND POWER COMPANY, OF NEW YORK, N. Y., A CORPORATION OF DELAWARE

IGNITION MECHANISM

Application filed May 3, 1928. Serial No. 274,777.

The present invention relates to an improvement in ignition apparatus adapted for various uses but particularly well adapted for use in connection with oil burning apparatus.

One of the objects of my invention is the provision of an ignition apparatus which is so constructed and arranged that the electrodes of the spark plug or igniter are moved automatically into and out of operative position with respect to the burner. Such an arrangement obviously is of advantage in that injury to the electrodes due to the heat of the burning fuel is prevented. It will be appreciated also that by moving the igniter out of firing position after ignition the igniter electrodes will be maintained free of oil and carbon.

In the accompanying drawings wherein I have illustrated an embodiment of my invention, Fig. 1 shows the same in plan and more or less diagrammatically;

Fig. 2 is a view similar to Fig. 1, showing parts of the igniter structure broken away;

Fig. 3 is a view partly in section of my improved apparatus as viewed from the rear thereof; and

Fig. 4 is a diagrammatic view showing the system of wiring.

Referring to the drawings in detail, my invention provides a spark plug or igniter 1, mounted in a base 2, and comprising two terminals 3 and 4. These terminals are bent laterally with respect to the longitudinal axis of the plug and these lateral portions are bent inwardly toward each other to provide a spark gap 5. The electrode 3 is mounted in the plug, while the electrode 4 is mounted in the base 2.

6 designates a spark plug clamp by which the plug proper is held in the base. The base 2, plug 1 and clamp 6 are all rotatable as a unit in a bearing 7 provided in a bracket 8, the complete assembly being held in this bearing by a bearing cap 9.

The plug clamp 6 is provided with a gear 10 which is in constant mesh with a rack 11 secured to an arm 12 mounted on a longitudinally movable shaft 13.

The arm 12 is held in place on the shaft 13

between two members 14 and 15 fixedly secured to said shaft.

The member 15 is in the form of a cap and receives one end of a coil spring 16 coiled about the shaft 13 and having the end opposite the cap 14 bearing constantly against the housing 17 of a torque motor 18. This torque motor, the construction of which, however, constitutes no part of the present invention, comprises a gear train designated 19 as a whole, the end gear or pinion 20 of this train meshing constantly with rack teeth 21 provided on the shaft 13. The shaft 13 as will be seen from Fig. 2 is mounted in bearings 22 and 23.

Obviously movement to the right as viewed in Fig. 2 of the shaft 13 under the action of the gear train 19 of the torque motor will effect rotation of the igniter in a clockwise direction, to carry the electrodes 3 and 4 from the full line position of Fig. 2 to the dotted line position of the same figure. This movement of the shaft 13 will of course place the spring 16 under tension and when the motor circuit is opened the shaft 13 and the igniter including the electrodes 3 and 4 will be restored automatically to their initial position.

The operation of the torque motor 18 and the supplying of current to the electrodes 3 and 4 of the igniter is controlled by an intermittently operated motor shown diagrammatically in Fig. 4 and designated 24. Current for jumping a spark across the gap 5 of the igniter is supplied by the secondary of a transformer 25, the primary of which is controlled by contact mechanism operated by the motor 24.

Current for the torque motor 18 and control motor 24 may be supplied from any suitable source.

Upon operation of a push button for example, current is supplied to the motor 24 by way of conductor 26, terminal 27, conductor 28, brush 29, armature of the motor 24, brush 30, conductor 31, terminal 32 to the other side of the line.

When the motor 24 has rotated sufficiently to bring the contact 33 carried thereby into engagement with the stationary contact 34 a circuit will be closed to the torque motor 18,

which circuit may be traced by way of conductor 26, terminal 27, conductor 35, armature of the motor 18, conductor 36, terminal 38, conductor 39, contacts 34, 33, contact 40, contact brush 41, conductors 42, 31, terminal 32 to the other side of the line.

The closing of the circuit to this torque motor will rotate or rock the electrodes 3 and 4 of the spark plug or igniter in a clockwise 10 direction from the full line position in Fig. 2 to the dotted line position in said figure.

A circuit is also closed at this time, that is, while the contacts 33 and 34 of the motor 24 are in engagement with each other, to the 15 primary of the transformer 25, by way of conductor 26, terminal 27, conductor 43, primary of the transformer, conductor 44, terminal 38, conductor 39, contacts 34, 33, 40, brush contacts 41, conductors 42, 31, terminal 20 32 to the other side of the line. The secondary of the transformer 25 has one side grounded as indicated at 45, the other side being connected to the electrode 3 of the spark plug or igniter by conductor 46. The 25 electrode 4 of the igniter is grounded.

The parts are so designed that when the electrodes 3 and 4 have been moved to their operative or firing position, i. e., the dotted line position of Fig. 2 and Fig. 4, the circuit 30 of the primary of the transformer 25 will have been opened and the current induced in the secondary will jump the gap 5 between the electrodes 3 and 4.

It will be understood, of course, that the 35 motor 24 is only intermittently operated, as distinguished from being continuously rotated, and consequently after the operation above described, that is after the electrodes of the igniter have been moved to firing position 40 the motor 24 is brought to rest with the contacts 33 and 34 out of engagement with each other which of course opens the circuit of the torque motor 17 so that the spring 16 may return all parts including the igniter 45 electrodes to their initial position.

As will be seen from Fig. 1 the spark plug or igniter is mounted at one side of the burner 47, so that when the igniter electrodes 3 and 4 are moved to their operative position the 50 gap 5 will be in the path of atomized fuel issuing from the nozzle of the burner 47, to ignite the same.

The bracket 8 above referred to, which carries the spark plug or igniter and may also 55 carry the torque motor 18 is mounted on a plate 48, which may be fastened to the front of the furnace. This arrangement of course may be varied as desired.

I have shown a blower 49 which supplies 60 the necessary air for atomizing the fuel fed through the burner 47, but the operation of this blower will not be described herein as the same forms no part of the present invention.

It will be seen from the foregoing that I 65 have provided an ignition mechanism which

is particularly adapted for use with oil burners or oil burning apparatus, which ignition mechanism is so constructed and arranged that the electrodes thereof are positively moved into and out of firing position. This is 70 of great advantage in this type of apparatus inasmuch as the electrodes or terminals of the igniter are protected from direct contact with the flame of the burner except at the instant of ignition or firing of the fuel, thereby preventing injury to the terminals or electrodes from this source. This arrangement also eliminates the carbonizing of the electrodes and hence faulty operation of the ignition system due to oil collecting thereon and becoming carbonized by the furnace heat. 75

I wish it to be understood that changes 80 may be made in the details of construction above described within the spirit and scope 85 of this invention.

What I claim is:—

1. In oil burning apparatus, the combination 90 of an igniter, a torque motor, a control motor, a transformer, said control motor being operative to make and break the circuit of said torque motor and said transformer, said torque motor being adapted to move said igniter into operative position with respect to the burner of the apparatus, and said transformer being operative when the igniter is in such position to supply ignition current thereto.

2. In combination an oil burner, an igniter 100 comprising cooperating electrodes, a support for said electrodes, a bracket for supporting said electrode support to one side of the burner, said electrodes being bent laterally with respect to the longitudinal axis of their support, means for rotating said electrodes about the axis of the electrode support to bring the electrodes into line with fuel issuing from the burner, and a spring for rotating the electrodes in the opposite direction to restore the same to initial position. 105

3. In combination with a furnace or combustion chamber, of an oil burner opening into the same, an igniter comprising a pair of electrodes projecting into the combustion chamber and bent laterally so as normally to lie to one side of the burner, a bracket adjacent the front of the furnace for mounting the igniter, means for imparting a rotary movement to the igniter in said bracket to swing the said electrodes about an axis parallel to the longitudinal axes of the electrodes into line with fuel issuing from the burner, and driving mechanism for reversing said movement of the electrodes to restore the same to their normal position. 110

4. In oil burning apparatus, the combination 115 of an igniter, a motor for moving the igniter into operative position with respect to the burner of the apparatus, means operative when the igniter is in operative position for supplying current to the igniter, and a control 120

motor for making and breaking the circuit of the first mentioned motor and the circuit of the said means for supplying current to the igniter.

- 5 5. Ignition apparatus for oil burners comprising a pair of cooperating electrodes, a rotary support for said electrodes, a bearing for said support, means operable independently of the heat of the burner for effecting
- 10 a partial rotation of said support to rotate said electrodes about an axis parallel to the longitudinal axis of said electrodes into operative position relative to the fuel issuing from the burner, and means for reversing
- 15 the movement of said support to restore the electrodes to their initial position.
6. The combination of an oil burner, an igniter comprising a spark plug provided with a pair of cooperating electrodes, said
- 20 electrodes being bent laterally with respect to the longitudinal axis of their support, an electric motor, a gear attached to said plug, a cooperating rack driven by said motor for rotating said electrodes about the axis of
- 25 the electrode support to bring the electrodes into line with fuel issuing from the burner, and means for rotating the electrodes in the opposite direction to restore the same to initial position.
- 30 7. The combination of an oil burner, an igniter comprising cooperating electrodes and a support for the electrodes, means for supporting the electrode support to one side of the burner, said electrodes being bent laterally with respect to the longitudinal axis of their support, means for rotating said electrodes about the axis of the electrode support and about an axis parallel to the axes of the electrodes to bring the electrodes into line
- 35 with fuel issuing from the burner, and a spring for rotating the electrodes in the opposite direction to restore the same to initial position.
- 40
- 45

This specification signed this 25th day of April, 1928.

JAMES N. MACRAE.
